COMBINATION ROLL AND ATTACHING DEVICE FOR IRONER ROLLS

John D. Willingham, Jr., 220 W. Paces Ferry Road,
Atlanta, Ga.Filed Feb. 8, 1960, Ser. No. 7,226
5 Claims. (Cl. 29—118)

This invention relates to flat work ironers and is more particularly concerned with a combination roll and attaching device for removably securing a lead cloth to the periphery of the roll attached to the periphery of a flat work ironer roll.

In the past, many and varied arrangements have been suggested for attaching the lead cloth of a pad assembly to the periphery of a flat work ironer roll. Probably the most conventional method of affixing the lead cloth to the periphery of the roll is to glue the end of the lead cloth in place on the periphery. Of course, this is a time consuming operation since the old pad assembly must be removed and the periphery of the roll cleaned. Also the work must be accomplished when the machine is shut down. Moreover, glue is messy and sometimes the adhesive bond breaks down during service. More recently, clipper laces have been employed for this purpose. The clipper lacing arrangement includes a metal plate permanently riveted or bolted in place on the periphery of the roll and provided with clipper laces along one edge thereof. Corresponding clipper laces must be provided along the end of the lead cloth so that when intermeshed with the clipper laces of the metal plate, a steel rod may be passed between the two to lock the respective clipper laces together. Once the plate carrying the clipper laces has been installed on the roll, it is difficult to remove. Further, the provision of clipper laces along the end of the lead cloth is expensive to manufacture and ship. Other methods of attachment include outwardly extending hooks which are bent with each new installation. U.S. Patent No. 2,663,974 discloses a hook type device. Such methods, however, usually include the permanent securing of a metal plate along the periphery of the roll and involve the bending of metal parts when a new roll is attached.

Contrary to prior art beliefs and practices, I have devised a combination roll and attaching device which may be readily removed from the roll when it is desired to change lead cloths or pads. This device includes a metal plate and a plurality of tines or prongs at spaced intervals along the metal plate. Holes or suitable apertures are provided in the roll to correspond to these tines. Usually, it is desirable to provide oversized holes or apertures in the periphery of the roll so that a relatively loose fit is provided when the metal plate is placed over the roll and the tines project into their corresponding holes. In some instances, it may be found desirable to provide points on the ends of the tines so that the tines may more readily pierce the end of the cloth. In some instances, it may also be desirable to provide bolts to hold down the metal plate on the roll.

Accordingly, it is an object of the present invention to provide a combination roll and attaching device for removably mounting the end of a lead cloth in place on the roll of the flat work ironer.

Another object of the present invention is to provide a combination roll and attaching device which will affix substantially any known type lead cloth to the periphery of the roll.

Another object of the present invention is to provide a combination roll and attaching device for a flat work ironer which is inexpensive to manufacture, durable in structure and efficient in operation.

Another object of the present invention is to provide

2

a combination roll and attaching device which requires no mating parts on the cover cloth and permits such a cloth to be readily removed and reversed, thereby extending its useful life.

5 Another object of the present invention is to provide an attaching device for securing a cloth to the periphery of a roll, the installation of which does not materially change the surface of the roll and hence does not prevent other methods from being subsequently used for attaching a cloth on the same roll.

10 Another object of the present invention is to provide a combination roll and attaching device which may be readily assembled to provide a positive means for securing the lead cloth to the roll of a flat work ironer.

15 Another object of the present invention is to provide a combination attaching device and a roll for a flat work ironer which may be readily assembled and disassembled so that the lead cloth of a pad may be readily installed or removed from the roll in an easy and efficient manner.

20 Another object of the present invention is to provide a combination attaching device and roll for a flat work ironer which will efficiently and firmly grasp and hold the end of a lead cloth of a pad and yet permit sufficient adjustment of the lead cloth after installation so that 25 the lead cloth may be made to track around the periphery of the roll accurately.

25 Other and further objects, features and advantages of the present invention will become apparent from the following description when taken in conjunction with the 30 accompanying drawings wherein like characters of reference designate corresponding parts throughout the several views and wherein:

35 FIG. 1 is a plan view of the combination flat work ironer roll and attaching device of the present invention, the lead cloth being shown in broken lines.

40 FIG. 2 is a fragmentary perspective view of the attaching device of FIG. 1, the device being in an inverted position.

45 FIG. 3 is a fragmentary perspective exploded view of the combination shown in FIG. 1.

45 FIG. 4 is a cross sectional view taken along line 4—4 in FIG. 1.

50 FIG. 5 is a cross sectional view taken along line 5—5 in FIG. 1.

55 FIG. 6 is a fragmentary side elevational view of a modified form of the attaching device of FIG. 1.

60 FIG. 7 is a plan view similar to FIG. 1 showing another modified form of attaching device being secured to the roll.

65 Referring now in detail to the embodiments chosen for purpose of illustration of the present invention, it being understood that the present invention is not limited to the exact structure disclosed in the accompanying drawings, numeral 10 denotes a conventional roll of a flat work ironer, the roll 10 being supported by its usual shaft 11 and end plates 12. According to the present invention, a plurality of radially extending, evenly spaced holes or apertures 13 are provided in the periphery of roll 10. The holes or apertures 13 are preferably aligned with each other in an axial direction across the entire periphery of roll 10. It will be understood, however, that these holes 13 may be staggered to a certain extent if desired and may be unevenly spaced without departing from the scope of the present invention.

65 The novel attaching device of the present invention is denoted generally by numeral 20 and includes a thin metal plate 21 having a length, approximately equal to the width of roll 10, and a relatively narrow width. The metal plate 21 is preferably arched or arcuate in a transverse direction to provide a concaved lower surface which is complementary with the outer periphery of roll 10 and a convexed upper surface. The plate 21 is also provided

with a straight leading edge 22 and a straight trailing edge 23 which are essentially parallel. The upper surface of the plate 21 is convexed so that when the plate is placed in a clamping position against the roll 10, it does not materially distort the even periphery of the roll.

Aligned longitudinally and projecting radially inwardly from the central portion of the inner surface of plate 21 are a plurality of evenly spaced, cylindrical tines or prongs 24. The tines 24 may be welded or bolted in place or may be affixed in any other suitable manner. The length of tines 24 is preferably about equal to the thickness of the wall of roll 10; however, it will be understood that substantially any length tine 24 may be provided, if desired. The end of the tine as seen in FIGS. 2 and 3 is flat; however, as seen in FIG. 6, tines, such as tines 124, may be substituted for the tines 24. It will be observed in FIG. 6 that the tines 124 are provided with pointed ends 125. The tines 24, or 124, are preferably of a diameter less than the diameter of the holes or apertures 13 so that each tine 24 or 124 may be loosely received within its oversize hole or aperture 13.

It will be observed that the spacing and arrangement of tines 24 or 124 corresponds to the spacing and arrangement of holes 13. Thus, when the attaching device is brought into registry with the periphery of roll 10, the tines 24 or 124 project into holes 13 respectively.

To hold the plate 21 in place on the periphery of roll 10, I have provided a plurality of bolts 26 which pass through appropriate apertures 27 in plate 21 and into holes 28 in the periphery of roll 10. The bolts 26 are provided with external threads which threadedly engage internal threads in holes 28.

In the modification shown in FIG. 7, it will be seen that the roll 10' is provided with a plurality of attaching devices 20' held in place in end to end abutting relationship on the periphery by bolts 26'. In the particular embodiment shown in FIG. 7, the inner end of plate 21' abuts against the inner end of the other plate 21' of the other attaching device 20' so as to provide the junction denoted by numeral 29. It will also be observed that only two bolts 26' are necessary to hold one of the attaching devices in place on the roll in end to end abutting relationship with respect to the other attaching device 20'. In the attaching device of FIG. 1, there is provided a central bolt 26 and two end bolts adjacent the opposite ends of the attaching device 20. The function of the bolts 26, 26' is simply to hold the attaching device in place on roll 10 or 10'. Thus, the bolts 26, 26' may be eliminated if desired.

In the preferred embodiment of the present invention, the plate 21 is formed of a sheet of metal $\frac{1}{16}$ inch thick, 3 inches wide and 100, 110 or 120 inches long, depending on the length of the roll. The tines 24 are studs $\frac{5}{16}$ inch in diameter and $\frac{3}{4}$ inch long. Preferably the attaching device is formed of a non-corrosive metal or galvanized to prevent rusting. Bolts 26 and 26' are large head $\frac{3}{8}$ inch bolts formed of non-corrosive material. The holes or apertures 13 are $\frac{1}{2}$ inch in diameter. The spacing between the tines 24 is 3 inches, hence the spacing of the holes or apertures is 3 inches.

From the foregoing description, the operation of the present device should be apparent. When it is desired to install a pad on a roll, such as roll 10 or 10', the attaching device 20 or 20' is removed by first removing bolts 26 or 26' and then lifting the plate 21. Next, the end of the lead cloth is placed over all of the apertures 13 and the attaching device 20 placed over the lead cloth with the tines 24 aligned with the holes 13. Next, pressure is exerted against the upper surface of plate 21 such as to cause the tines 24 to pierce the fabric of the lead cloth 30 or 30' and enter the apertures or holes 13. In this operation, the tines 24 or 124 and holes 13 cooperate as punches and dies to shear or punch out the fabric.

Next, the bolts 26 are passed through holes 27 and into holes 28. By rotating the bolts 26, they are tightened

within the holes 28 so as to retain the plate 21 in place on roll 10. It will be observed that the holes 27 are in front of the tines 24 and are adjacent the edge 23 of plate 21. Thus, if the edge of the lead cloth 30 terminates between the tines 24 and hole 27, it is not necessary for the bolts 26 to pass through the lead cloth 30.

Of course, in some instances it may be found desirable to have the plate 21 overlap an intermediate portion of lead cloth 30. In this instance, the bolts 26 must be urged through the fabric of the lead cloth to project into hole 28.

Next, the lead cloth 30 is wrapped around the roll 10 in conventional manner and the remaining portion of the pad is installed in the usual way. If the lead cloth 30 or 30' is out of alignment with the roll 20, it is only necessary to unroll the lead cloth to the position shown in FIGS. 1 and 7 and then exert sufficient tension against the short side of the lead cloth to cause slight realignment of the lead cloth. When the lead cloth 30 or 30' passes over the plate, such as plate 21, after being wrapped around the roll, it will retain the plate in place, regardless of the action of bolts 26. The pointed ends 125 of tines 124 simply facilitate the insertion of the tines through the rear edge of the lead cloth 30. With the cloth 30 or 30' wrapped around the roll at least once, the force exerted against the cloth 30 or 30' will have a tendency of tightening it about roll 10 or 10'. The tightening of the cloth 30 or 30' in turn tends to urge the device 20 or 20' downwardly against roll 10 or 10' and thereby increase the clamping force of the plate 21 or 21'.

On the other hand, if the cloth 30 or 30' is relatively loose and receives a sudden jerk, which is transmitted to the attaching device 20 or 20', the device will tend to rotate in the oversize holes 13. This tendency to rotate will urge the edge 22 against the cloth 30 or 30' and thus clamp more firmly the cloth 30 or 30'.

Two clamping actions described above, acting in conjunction with each other, provide a positive and very firm grip upon the fabric, separate and apart from the gripping action of the tines alone.

It will be obvious to those skilled in the art that many variations may be made in the embodiments here disclosed for the purpose of illustrating the present invention without departing from the scope thereof as defined by the appended claims.

I claim:

1. In a flat work ironing system of the class wherein a cloth is attached to the periphery of the roll, the combination with said roll of an attaching device, there being provided along the periphery of said roll a plurality of aligned, evenly spaced holes, said attaching device comprising a thin metal plate having a length about equal to the width of said roll and a relatively narrow width, said plate being arcuate to provide a concaved lower surface corresponding to the curvature of the periphery of said roll and convexed upper surface, said plate being provided with parallel front and back edges, a plurality of evenly spaced, cylindrical, pointed, tines projecting from the inner surface of said plate inwardly through said holes respectively, said tines being so constructed and arranged as to be freely movable axially into and out of said holes, and means for removably securing said plate to said roll, whereby said tines project through the fabric of said cloth to retain said cloth on said roll, said holes being oversized with respect to said tines so as to receive said tines loosely.

2. In a flat work ironing system of the class wherein a cloth is attached to the periphery of the roll, the combination with said roll of an attaching device, there being provided along the periphery of said roll a plurality of aligned, evenly spaced holes, said attaching device comprising a thin metal plate having a length about equal to the width of said roll and a relatively narrow width, a plurality of tines projecting from the inner surface of said plate inwardly through said holes respectively, said tines

being so constructed and arranged as to be freely movable axially into and out of said holes, and means for removably securing said plate to said roll, whereby said tines project through the fabric of said cloth to retain said cloth on said roll.

3. In a flat work ironing system of the class wherein a cloth is attached to the periphery of the roll, the combination with said roll of an attaching device, there being provided along the periphery of said roll a plurality of aligned, evenly spaced holes, said attaching device comprising a thin metal plate extending over said roll, and a plurality of tines projecting from the inner surface of said plate inwardly through and journaled for free axial movement in said holes respectively.

4. The structure defined in claim 3 wherein said tines are pointed.

5. In a flat work ironing system of the class wherein a cloth is attached to the periphery of the roll, the combination with said roll of an attaching device, there being provided along the periphery of said roll a plurality of aligned, evenly spaced cylindrical holes, said attaching

5 device comprising a thin metal plate having a length about equal to the length of said roll and a relatively narrow width, said plate being arcuate to provide a concaved lower surface corresponding to the curvature of the periphery of said roll and a convexed upper surface, said plate being provided with parallel front and back edges, a plurality of cylindrical tines projecting from the inner surface of said plate inwardly through said holes respectively said tines being approximately the diameter of said holes and provided with points, bolts passing through said plate and into said roll for securing said plate to said roll, whereby said tines project through the fabric of said cloth to retain said cloth on said roll.
